Eccleston & Eccleston,
Attorneys

UNITED STATES PATENT OFFICE.

HARRY A. NUTTER, OF SEYMORE, INDIANA.

ADJUSTABLE SHADE-ROLLER BRACKET.

Application filed August 30, 1923. Serial No. 330,112.

To all whom it may concern:

Be it known that I, HARRY A. NUTTER, a citizen of the United States, residing at Seymour, in the county of Jackson and State 5 of Indiana, have invented certain new and useful Improvements in Adjustable Shade-Roller Brackets, of which the following is a full, clear, and exact description.

The present invention relates to a bracket 10 for shade rollers and has for its object to provide such a device which is adjustable so as to receive rollers of varying lengths.

Another object of the invention resides in so attaching the brackets to the window casting or jamb that the curtain will be automatically centered with respect to the window with which it cooperates.

A further object of the invention resides in the construction of a bracket which 20 though adjustable will, nevertheless, allow the shade to hang close to the window.

Another object of the invention consists in so designing an adjustable bracket that the same will be composed of a minimum 25 number of parts; such parts being easily and cheaply assembled.

Other objects and advantages of the invention will be apparent from the following description when taken in connection with 30 the accompanying drawings, in which,

Figure 1 is a fragmentary elevational view of a window showing my adjustable brackets in position.

Figure 2 is an end view of one of the 35 brackets.

Figure 3 is a front elevation of a bracket.

Figure 4 is a longitudinal section taken on line 4—4 of Figure 2.

Figures 5 and 6 are enlarged fragmentary 40 perspective views of the arms for receiving the respective ends of the roller, and,

Figure 7 is a reduced plan of the blank from which the body portion of the bracket is formed.

Referring to the drawings more in detail, the numeral 1 indicates a common type of window casing or jamb in which is mounted the window proper 2. The window shade is designated by the numeral 3 and is attached to the usual roller 4. In lieu of the flat metal brackets in common use for supporting the ends of the roller 4 I have provided the adjustable, self-centering brackets 5. These brackets are shown in operative 50 position in Figure 1 of the drawings, but are disclosed in detail in Figures 2 to 7 includ-

sive; and I will now proceed to describe the device with respect to its various details.

The numeral 6 designates a cylinder bent up from section "A" of the sheet metal blank shown in Figure 7, so as to leave a slot 7 extending throughout the length thereof. The slot thus formed will obviously be located at a point slightly forward of the bottom of the cylinder 6, and will thus permit 65 the roller-supporting arm, to be later described, to be positioned very close to the window. The blank shown in Figure 7 comprises in addition to the section "A", a rectangular section "B" and connecting portion "C". The section "B" of the blank is bent up to form a flange 8 while the connecting portion "C" is rounded out to form a connecting web 9 between the cylinder 6 and flange 8. The flange 8 is provided with 70 suitable apertures by which the bracket is secured to the outer edge of a window casting or jamb as shown in Figure 1.

Mounted on the ends of the cylinder 6 are flanged caps 10 and 11, which are centrally 80 apertured for the reception of a screw or other fastening means 12. These screws 12 secure the caps to the ends of a rod 13 which is positioned longitudinally of the cylinder 6. Slidably mounted on the rod 13 is an 85 arm 14 which extends through the slot 7 and is provided with a recessed boss 15 for the reception of one end of the shade roller 4. This arm is normally forced toward the free end of the cylinder 6 by means of a compression spring 16 which surrounds the rod 13 and engages one of the caps 12 and arm 14.

In Figure 6 is shown a fragmentary perspective view of an arm 14' which is the companion of the arm 14 in that it is provided with a cylindrical recess to serve as a bearing for the cylindrical projection usually found at one end of a shade roller.

In operation, the shade and roller are hung by merely pressing outwardly on the 100 arms 14 and 14' until these arms are sufficiently spaced to receive the ends of the roller in the usual manner; the distance between the arms 14 and 14' depending, of course, upon the length of roller employed. 105 The springs 16 will now move the arms toward each other with sufficient force to firmly hold the roller in position.

The device as above described may be termed a self-centering bracket in that, as 110 shown in Figure 1, it is secured to the outer edge of the window casing 1, and must of

necessity hold the curtain at equal distances from these edges. It might also be here noted that the construction and arrangement of the cylinders and arms are such 5 that the curtain will hang close to the window rather than at a distance therefrom, and in this respect the present structure is a distinct improvement over prior adjustable brackets with which I am familiar. 10 Furthermore, it will be seen that this bracket is not only adapted to receive rollers of varying lengths due to the fact that the positions of the arms may be varied, but also is so 15 designed that the several parts may be stamped from sheet metal, or cast, and may then be easily and quickly assembled.

In accordance with the patent statutes I have described what I now believe to be the best embodiment of the invention, but 20 I do not wish to be understood thereby as limiting myself or the scope of the invention, as many changes and modifications may be made without departing from the spirit of the invention; all such I aim to include in 25 the scope of the appended claims.

What I claim as new and desire to secure by Letters Patent is:

1. A shade roller bracket formed from a blank of sheet metal, one portion of the blank being bent up to form an attaching 30 flange, and another portion of the blank being bent into a substantially cylindrical form but having two of its edges spaced so as to form a longitudinal slot, and an arm slidably mounted in said cylinder with one 35 of its ends protruding through said slot.

2. A shade roller bracket formed from a blank of sheet metal, one portion of the blank being bent up to form an attaching flange, and another portion of the blank 40 being bent into a substantially cylindrical formation but having two of its edges spaced so as to provide a longitudinal slot, said flange and cylinder being disposed at right angles, an arm slidably mounted in said 45 cylinder with one of its ends protruding through said slot, and spring means tending to force said arm toward one end of the cylinder.

HARRY A. NUTTER.
